UNITED STATES PATENT OFFICE.

LEONARD L. FERGUSON, OF CHICAGO, ILLINOIS, ASSIGNOR, BY MESNE ASSIGNMENTS,
TO DUNTLEY PNEUMATIC SWEEPER COMPANY, OF CHICAGO, ILLINOIS, A CORPO-
RATION OF ILLINOIS.

CLEANING DEVICE.

1,239,581.

Specification of Letters Patent. Patented Sept. 11, 1917.

Application filed January 10, 1913. Serial No. 741,144.

To all whom it may concern:

Be it known that I, LEONARD L. FERGUSON, a citizen of the United States, residing at Chicago, in the county of Cook and State 5 of Illinois, have invented a certain new and useful Improvement in Cleaning Devices, of which the following is a full, clear, concise, and exact description, reference being had to the accompanying drawing, forming

10 a part of this specification.

My invention relates to cleaning devices and has for its object the provision of an improved device of this character which combines both pneumatic apparatus for 15 cleaning purposes and also sweeping or similar apparatus, both kinds of apparatus working in harmony to effect a thorough cleaning of the objects which they are to clean.

20 In general it may be said that the pneumatic cleaning devices take up and gather the smaller dust particles which are to be removed from the object to be cleaned, whereas the sweeper or similar apparatus 25 removes the heavier particles, which the pneumatic apparatus generally, or at least frequently, fails to remove. The sweeper apparatus also serves to loosen certain impurities which are then more readily gathered in by the pneumatic apparatus.

30 My invention concerns itself particularly with the arrangement and construction of a device of this character in which the various component parts may be readily taken 35 apart and in which the gathered impurities may be most readily removed. The compartment within which the sweeping apparatus operates is removable bodily from the device, thus to dump the impurities therein 40 gathered after sweeping, it not being necessary to mount any of the walls of this compartment in a tilttable manner as the entire compartment is adapted for removal. This compartment also preferably carries the 45 mouthpiece used with the pneumatic apparatus, and the parts are so arranged that an airtight connection is readily established for the connection of this mouthpiece with the rest of the pneumatic elements.

50 My invention further contemplates a very readily removable dust bag. My invention also contemplates a flexible mounting of the wheels so as to accommodate the brushes more readily to the surfaces over which 55 they are operable.

I will explain one embodiment of my invention more in detail by reference to the accompanying drawing, in which—

Figure 1 is a longitudinal sectional view 60 of my improved device;

Fig. 2 is a side elevation of the front end of the main body and of the sweeper and nozzle showing the separability of the parts;

Fig. 3 is a top view of the dust bag;

Fig. 4 is a top view of the sweeper compartment and mouthpiece.

Referring more particularly to Fig. 1 I show my improved device as comprising a wall 1 surmounted by a suitable cover 2 to form a compartment 3. Within this compartment 3 bellows 4, 4, 4 are mounted which through the agency of suitable connecting rods 5 are connected with a crank shaft 6, which crank shaft is held in suitable bearings 7 and carries wheels 8 adapted 70 to roll over the floor. These wheels when the device is moved to and fro impart rotation to the crank shaft, and thereby successively operate the bellows 4 which maintains a continuous suction while the device 80 is in operation. A suitable handle 9 is pivotally mounted at 10 so that the device is suitably under manual control.

Below the wall 1, I provide what I may call a dust compartment 11 which is closed 85 on all of its sides except the front end thereof as at 12. A suitable passageway 13 leads from each bellows 4 into this dust compartment so as to establish a suction therein. A suitable screen 14 is provided 90 to prevent a dust bag 15 from entering the passageway 13 and this dust bag is suitably secured to a mouthpiece 16 adapted to fit snugly the opening at 12 in the dust compartment. A U-shaped spring 37 is adapted 95 to be sprung into holes provided in the opposite sides of the mouthpiece 16 so that this spring holds the bag 15 in a substantially open condition so as to present the very largest possible surface of said bag 100 to the suction apparatus, thereby preventing crinkling of the bag. A suitable gasket 17 is provided on the outer face of this mouthpiece 16 so as to provide airtight connection with a mouthpiece 18 as will presently appear. The impurities are thus sucked through the opening 19 in the mouthpiece 18 and into the bag 15, which bag separates the impurities from the air so that these impurities may thereafter be removed 110

by merely taking out the dust bag and emptying the same.

Below the dust compartment 11, I provide a couple of guides 20 by means of which an impurities compartment or dust chamber 21 may be slid into place, which impurities compartment is preferably fixedly secured to the mouthpiece 18. This impurities compartment has lower walls 22, 22 having flaring extensions 23 and these walls are preferably integral with the side walls of this impurities compartment. This impurities compartment is formed of one piece to form a sort of cup shaped structure which may then be fastened to the mouthpiece 18. In this way a very simple and efficient sweeper brush compartment is provided which can be readily removed to dump the sweepings and likewise to properly expose the brush of the sweeper for cleaning. It is not necessary to mount the walls 22 in a tiltable manner as the upper portion of this impurities compartment when removed from the dust compartment is entirely open and this impurities compartment may thus be readily emptied.

Two wheels 24, 24 are mounted on opposite sides upon a shaft 25, which shaft projects through openings 26 in the sides of the impurities compartment, these openings being larger than the shaft so as to permit movement of this shaft to thereby permit the wheels 24 to adjust themselves with respect to the broom portion 27. This shaft 25 is pressed downwardly by a spring 28 held in a bridge piece 29 forming part of the impurities compartment structure. Two brackets 30 are mounted on opposite sides of the impurities compartment structure and are held in place by screws 31, these brackets 30 not being in engagement with the wheels 24 or shaft 25. The wheels 24 bear against friction rollers 33 to thereby drive the brush 27. A projecting tube 34 is fastened to the mouthpiece portion and is adapted to project into the opening within the mouth portion 17 so that dust entering the duct 19 is conveyed directly to within the bag 15. The front portion of the brush and mouthpiece structure is provided with springs 35 by means of which the two parts are held together through the agency of the clamping yoke 36.

Now in order to separate the device and remove all of the impurities gathered, it is merely necessary to swing the yoke 36 out of engagement with springs 35, whereafter the impurities compartment and mouthpiece structure is bodily slid away from engagement with the guides 20 and this impurities compartment may be emptied. To remove the refuse gathered within the bag

15 all that is necessary is to remove this bag and mouth portion 17 from its normal position and empty the bag.

It will thus be seen that a very simple and readily operable structure is provided for cleaning purposes. It will of course be understood that many modifications may be made from the specific structure herein shown, and my invention contemplates such modifications, and what I therefore claim as new and desire to secure by Letters Patent is:—

1. In combination with a vacuum cleaning machine having a dust box, a dust inlet nozzle, vacuum creating means and a supporting wheel, of a carpet sweeper having a dust chamber, a brush and brush driving wheels, and means for detachably connecting the carpet sweeper as a unit and for withdrawing it from below the dust box of the vacuum cleaning machine, the sweeper being located between the inlet nozzle and the supporting wheel.

2. In combination with a vacuum cleaner having a body portion provided with a vacuum creating means and a dust box, a supporting wheel and a dust inlet nozzle, the nozzle being supported at one end of the body and the wheel at the opposite end thereof, of a sweeper comprising a casing, supporting wheels, a brush and dirt collecting chamber, said nozzle and said sweeper being removable, the body having means for detachably engaging the nozzle and attaching means to engage the sweeper casing.

3. In a vacuum cleaner, the combination with a suction creating device and a detachable inlet nozzle therefor, of a carpet sweeper secured to said nozzle and having a brush adapted to engage the surface to be cleaned, and attaching means to engage the sweeper and the nozzle to maintain them in operative position and permitting the sweeper and nozzle to be detached as a unit from the suction creating device.

4. In combination, a vacuum cleaner, a carpet sweeper comprising a dust chamber, a brush and brush-driving wheels mounted on the chamber, said chamber being arranged below and connected to the body of the vacuum cleaner, and means whereby the said carpet sweeper may be readily detached as a unit and withdrawn from below the body of the vacuum cleaner.

In witness whereof, I hereunto subscribe my name this 19th day of December, A. D., 1912.

LEONARD L. FERGUSON.
